T. L. LA MALTA

HOLLOW BLAST GRATE BAR

Filed April 19, 1919

Fig. 2.

Inventor
Thomas L. LaMalta.

By Al Readford
Attorney

UNITED STATES PATENT OFFICE.

THOMAS LOUIS LA MALTA, OF MEMPHIS, TENNESSEE.

HOLLOW-BLAST GRATE BAR.

Application filed April 19, 1919. Serial No. 291,337.

To all whom it may concern:

Be it known that I, THOMAS L. LA MALTA, a citizen of the United States, residing at Memphis, in the county of Shelby and State 5 of Tennessee, have invented certain new and useful Improvements in Hollow-Blast Grate Bars, of which the following is a specification.

My said invention consists in an improved 10 construction of hollow blast or forced draft grate bars for use in steam boiler furnaces, the principal object being to provide a bar of such type which can be readily cleaned while the furnace is in operation; and also to provide a structure whereby such purpose may 15 be readily and conveniently accomplished, all as will be hereinafter more fully described and claimed.

Referring to the accompanying drawing, 20 which is made a part hereof and on which similar reference characters indicate similar parts,

Figure 1 is a view of a portion of a grate 25 of the type referred to in end elevation, one of the grate bars being shown in cross section to illustrate the construction more clearly, and

Figure 2, a side elevation, one end of the 30 bar being shown in section to illustrate the construction more clearly.

The grate bars 10 are in themselves of any particular form desired, the form illustrated being shown only for the purpose of illustrating the invention. Each bar is hollow 35 and preferably provided with an angular top perforated as shown. The several bars composing the grate are each connected near one end to a hollow blast intake pipe 11 and in the opposite extreme end each bar is 40 formed with an opening closed by a door 12. Each door is provided with hinge-parts 13 and they are mounted on pintles or cross pins 14 which are secured in the sides of the bar. Underneath each grate bar, near the 45 end containing the opening and the door 12, is mounted a shaft 15 journaled in suitable bearings on the under sides of the grate bars and extending entirely across the grate. Opposite each door 12 a curved 50 arm or a cam 16 is secured on said shaft adapted to bear against the outer face of the door as best illustrated in Figure 2. An operating lever 17 is mounted upon said shaft.

Said cams 16 are each formed with a straight face 20 adapted to support the door when in 55 open position.

It will thus be seen that by swinging the lever 17 from the position shown in whole lines to the position shown in dotted lines in Figure 2 cam 16 will operate to swing door 12 inwardly on its hinge 14 and support said door in a horizontal position as illustrated by dotted lines in said figure. The swinging of shaft 15 operates the entire series of cams 16 and doors 12 as will be readily understood. When the doors are swung open in this manner the blast immediately drives from the grate bars the accumulation of ashes, cinders, etc., thus serving to quickly clean the grate without interfering with the 70 operation of the furnace. It will be understood that other means for opening and closing the doors may be provided, as well as other modifications in the details, without departing from my invention, as defined in 75 the claims.

Having thus fully described my said invention, what I claim as new and desire to secure by Letters Patent, is:

1. A hollow grate bar connected near one 80 end with a blast line, a door pivoted at its upper edge to the bar at the opposite end and swinging inwardly, a curved arm pivoted adjacent the door and adapted to swing with its extremity within the bar and a cam 85 carried upon the extremity adapted to engage and open the door and provided with means for supporting the door in open position and co-operating with the door to prevent return movement of the arm. 90

2. The combination with a hollow grate bar, of a door hinged at its upper edge to swing within one end of the bar, a curved arm fulcrumed adjacent to the door and adapted to swing with its extremity moving the door within the bar, and provided on its outer edge with a portion struck upon a chord of the arc with the fulcrum as the center, said portion adapted to form a support for the door in its open position. 95

3. The combination with a hollow grate bar of a door hinged at its upper end to swing within one end of the bar, and an arm fulcrumed adjacent to the door and adapted to swing with one end moving the door within the bar and provided on said 100 105

end with a flat surface for supporting the door in its open position and co-operating with a flat surface on the door to prevent return movement of the arm, substantially as set forth.

In witness whereof, I have hereunto set my hand and seal at Memphis, Tennessee,

this 14th day of April, A. D. nineteen hundred and nineteen.

THOMAS LOUIS LA MALTA. [L.S.]

Witnesses:

MATT DWYER,
W. H. IRWIN.
